Primary Examiner—Cathron Brooks*Assistant Examiner*—Kevin K Rudzinski(74) *Attorney, Agent, or Firm*—Harness, Dickey & Pierce, P.L.C.(57) **CLAIM**

The ornamental design for a low profile light source, as shown and described.

DESCRIPTION

FIG. 1 is a top, front perspective view of a low profile light source showing our new design;

FIG. 2 is a bottom, rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof;

FIG. 9 is a cross-sectional view taken along line 9—9 of FIG. 5; and,

FIG. 10 is a cross-sectional view taken along line 10—10 of FIG. 5.

The wire-like elements, in FIGS. 1—6, are shown having indeterminate length.
